UNITED STATES PATENT OFFICE

136,137

DESIGN FOR A CURTAIN ROD BRACKET

Phillip L. Teninty, Stockton, Calif.

Application May 25, 1943, Serial No. 110,279

Term of patent 7 years

To all whom it may concern:

Be it known that I, Phillip L. Teninty, a citizen of the United States, residing at Stockton, in the county of San Joaquin and State of California, have invented a certain new, original, and ornamental Design for a Curtain Rod Bracket, of which the following is a specification, reference being had to the accompanying drawing, forming a part thereof.

Figure 1 is a perspective view of a curtain rod bracket, looking at one side, showing my new design.

Figure 2 is a similar view, looking at the opposite side.

I claim:

The ornamental design for a curtain rod bracket, as shown.

PHILLIP L. TENINTY.
